US0D1096735S

(12) **United States Design Patent** (10) Patent No.: **US D1,096,735 S**
(45) Date of Patent: ** *Oct. 7, 2025

(54) **COMPUTING INPUT DEVICE**

(71) Applicant: **Microsoft Corporation**, Redmond, WA (US)

(72) Inventors: **John Helmes**, Limburg (NL); **Aditha May Adams**, Seattle, WA (US); **Simon Cameron Dearsley**, Bellevue, WA (US); **Go Osaki**, Shenzhen (CN); **Hongshan Sun**, Shenzhen (CN)

(73) Assignee: **Microsoft Corporation**, Redmond, WA (US)

(*) Notice: This patent is subject to a terminal disclaimer.

(**) Term: **15 Years**

(21) Appl. No.: **29/945,610**

(22) Filed: **Jun. 4, 2024**
